UNITED STATES PATENT OFFICE.

WILLIAM NICHOLAS, OF SOUTHPORT, CONNECTICUT, AND WILLIAM ACKERMAN, OF BROOKLYN, NEW YORK, ASSIGNEES TO PREMIER MACHINE COMPANY, A CORPORATION OF DELAWARE.

GALLEY-BLOCK.

1,231,636.

Specification of Letters Patent.

Patented July 3, 1917.

Application filed July 7, 1914. Serial No. 849,577.

To all whom it may concern:

Be it known that we, WILLIAM NICHOLAS, a subject of the King of Great Britain, residing in the town of Southport, county of 5 Fairfield, and State of Connecticut, and WILLIAM ACKERMAN, a citizen of the United States, residing in the borough of Brooklyn, city of New York, county of Kings, and State of New York, have invented new and 10 useful Improvements in Galley-Blocks, fully described and represented in the following specification and the accompanying drawings, forming a part of the same.

Our invention relates to printers' appliances and has for an object to provide an 15 expandible foot block for galleys which may be used for various column widths from a predetermined minimum to any required width.

20 In the practice of our invention we use a rectangular block having two side members similar in construction and slidably secured together so as to maintain parallel outer sides in all adjusted positions. At 25 either one or both sides of the block we employ supplemental blocks of substantially the same length as the resilient member, of predetermined widths which are preferably made in two sizes, one of which is two pica 30 ems in width and the other five pica ems wide, either of which may be attachably secured to a side of the resilient block and additional members added to bring the 35 width of the galley block to the desired pica measurement.

In actual practice there is rarely occasion to have a column less than six pica ems, therefore our resilient member is adapted to be expanded from that width 6 pica 40 ems, to double the size or 12 picas.

In the accompanying drawings, illustrative of a preferred form of our device, Figure 1 is an under plan view of our improved block, not expanded, not in place in 45 a type holding galley; Fig. 2 is a similar view of a non-resilient, supplemental component of the galley block; Figs. 3 and 4 are similar sectional views, the former on line 3—3 of Fig. 1, the latter on line 4—4 of 50 Fig. 2; Figs. 5 and 6 are respective end views of the resilient and supplemental blocks; and Fig. 7 shows the block in position in a galley.

Referring to the drawings: 1 represents

the usual type of printer's galley having the 55 side walls 2 between which our galley block is adapted to be held as it is slid lengthwise of the galley as the matter is fed therein when used in connection with a type setting machine. The galley block 3 is not a single 60 member, but composed of a resilient member 5 and supplemental blocks 10 made preferably in two sizes, one measuring two ems, the other five ems, having reference to their 65 normal position in the galley. The resilient 70 block 5 has two similar side pieces, one of which is slidably mounted on the other, by means of the guide portions 7 at the respective 75 ends thereof. Within the side pieces 6 mounted upon suitable bosses 4^a provided 80 for the purpose are two similar compression springs 4 which are adapted to press the side pieces apart until the pins 8 on the guides at both ends of each of the side pieces 85 impinge against stop extensions 9 provided 90 at the corresponding ends at the other of the side pieces. The stops 9 and pins 8 are suitably placed at the respective outer ends of the guides 7 and as the latter move in relation one to the other, the pin recedes from 95 the stop to the full extent of the compression of the springs which in the form illustrated admits of a collapsible movement of 3 pica 100 ems. Hence as the width of the preferred form of block in full compression is 6 pica 105 ems, it may be expanded to the limit of three pica ems additional.

In the sides of the resilient member at either end are the orifices 13, into which are adapted to fit tongue pieces 11 suitably extending from one side of each of the supplemental blocks 10, similar orifices 12 being provided in the opposite faces of all of said supplemental blocks for receiving the corresponding piece of additional blocks in the 115 same manner. A projecting thumb piece 14 is provided upon the end of the block 5, or more particularly described as projecting from one of the guide members 7 constituting the ends of the corresponding side pieces 120 6, by means of which thumb piece the block 5 may be lifted easily when it is desired to 100 remove it from the galley in which it has been serving its purpose.

Thus it will be seen that when the resilient block having a capacity of expanding through 6 pica ems, by the use of blocks having 2 and 3 pica em width measurement, by

employing the required number of such supplemental blocks 10, the galley block can be widened to any column measurement and being in place at the foot of the column 5 therein, by action of the springs will be held with the same frictional pressure irrespective of the number of supplemental blocks employed in connection therewith.

Having described our invention, what we 10 claim is:

1. A galley block having parallel side pieces substantially similar in form and oppositely disposed, means for mounting one of said pieces slidably upon the other of said 15 pieces; and means comprising two similar compression springs adapted normally to ex-

pand said side pieces substantially in the manner and for the purposes described.

2. A galley block and means for expanding its sides laterally in combination with 20 supplemental blocks and means for operably connecting such expandable and supplemental blocks substantially in the manner and for the purposes described.

In testimony whereof, we have hereunto 25 set our hands in the presence of two subscribing witnesses.

WILLIAM NICHOLAS.
WILLIAM ACKERMAN.
